(57) **CLAIM**

The ornamental design for a cam for a coupling as shown and described.

DESCRIPTION

FIG. 1 is a front view of a cam for a coupling of our new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front perspective view thereof;

FIG. 8 is a rear perspective view thereof;

FIG. 9 is a sectional view thereof, taken along the line 9-9 of FIG. 1;

FIG. 10 is an enlarged front view thereof, taken along the lines 10-10 and 10'-10' of FIG. 1;

FIG. 11 is an enlarged sectional view thereof, taken along the lines 11-11 of FIG. 9; and,

FIG. 12 is a partial enlarged perspective view thereof.

The broken lines show portions of a cam for a coupling that form no part of the claimed design.

1 Claim, 12 Drawing Sheets
